United States Patent Office.

PAUL DECHAUSE, OF NEW YORK, N. Y.

Letters Patent No. 71,858, dated December 10, 1867; antedated November 23, 1867.

PAINTER'S EASEL.

The Schedule referred to in these Letters Patent and making part of the same.

TO ALL WHOM IT MAY CONCERN:

Be it known that I, PAUL DECHAUSE, citizen of France, now residing at No. 894 Broadway, in the city of New York, in the county and State of New York, have invented a new and useful Improvement in Easels; and I do hereby declare that the following is a full, clear, and exact description thereof, which will enable those skilled in the art to make and use the same, reference being had to the accompanying drawing, forming part of this specification, in which drawing—

Figure 1 represents an easel made according to my invention, in the act of being extended and adjusted in position upon uneven ground.

Figure 2 is a vertical or longitudinal section from front to rear, taken when the easel is folded up.

Figure 3 is a cross-section, taken on the line $x\pi$, fig. 2, the easel being partly opened out.

Similar letters indicate corresponding parts.

The object of this invention is, among other things, to produce an easel for artists, or for other purposes, which can be securely and safely placed on uneven ground, and also adjusted to varying heights to suit the frame or picture, or the stature of the person using the easel.

The easel is represented in fig. 1 in the act of being adjusted upon uneven ground. The legs *a a a* are each made extensible by sliding extensions *b b b*, which are connected to the legs by straps *h h*, one of which is fastened to the legs *a*, and the other to the extension-pieces *b*. The extension-pieces are secured in the desired relations to the legs, more or less extended, by set-screws *i*. In order to secure the easel when extended, and to give it steadiness or firmness, I provide a toggle-joint, *c c*, which, when fully extended, acts as a brace to those legs to which it is directly connected, and prevents them from collapsing or coming together. The parts *c c* of the toggle are hinged by their outer ends to two of the legs *a a*, while their inner ends are hinged to each other. Their hinged ends are provided with a tongue, *j*, which is fitted in a longitudinal groove made in the back of the rest *c* of the easel, as is clearly shown in figs. 2 and 3. When the said legs *a a* are brought together, the toggle folds up and its tongue *j* slides upwards towards the top of the groove, as is represented in fig. 2. When the legs are distended, the tongue slides down towards the bottom of the groove, and allows the toggle to take a horizontal position, in which position it acts as a brace to the said legs. Fig. 1 represents the toggle partly drawn down to its proper horizontal position. The legs *a a a* are hinged at *l l l* to the head *k* of the easel. The rest *d e* which supports the picture is made extensible by connecting the parts *d e* to each other with a tongue and groove, as is shown in the cross-section, fig. 3, the front part, *d*, being movable on the part *e*, and the latter being fixed permanently to the head *k*. The lower end of the movable part *d* is provided with an immovable clamp, *f*, which is secured in place by a set-screw, and its upper end has a clamp, *g*, which is movable and adjustable vertically on the face of the rest. The set-screw that fastens the lower clamp also fastens the sliding part *d* of the rest to the fixed part *e*. The top of clamp *f* and the bottom of clamp *g* have fingers *m*, which serve to hold the frame or picture upon the easel, and prevent it from becoming displaced on the rest.

What I claim as new, and desire to secure by Letters Patent, is—

1. The extensible legs, consisting of the hinged legs *a* and their extension sliding parts *b*, made and arranged substantially as described.

2. I also claim the combination of the legs with the toggle-brace *c c*, substantially as described.

3. I also claim the extension rest, comprising the fixed and movable clamps *f g*, substantially as described.

PAUL DECHAUSE.
